L. C. DOANE

LIGHTING FIXTURE

Filed July 26, 1921

INVENTOR:

LEROY C. DOANE,

BY *Albert G. Davis*

HIS ATTORNEY.

UNITED STATES PATENT OFFICE.

LEROY C. DOANE, OF CLEVELAND, OHIO, ASSIGNOR, BY MESNE ASSIGNMENTS, TO THE MILLER COMPANY, OF MERIDEN, CONNECTICUT, A CORPORATION OF CONNECTICUT.

LIGHTING FIXTURE.

Application filed July 26, 1921. Serial No. 487,734.

To all whom it may concern:

Be it known that I, LEROY C. DOANE, a citizen of the United States, residing at Cleveland, in the county of Cuyahoga, State of Ohio, have invented certain new and useful Improvements in Lighting Fixtures, of which the following is a specification.

My invention relates to illuminating equipment and more specifically to colored 10 illuminating equipment.

In display illumination such as used with show windows, bill-boards, etc., it is frequently desired to use colored light. It is also desired that the colored light may be 15 changed at will with a minimum of inconvenience and expense. The use of colored lamps does not readily give the small consumer the range of color which is desired and is comparatively expensive as the use of 20 colored lamps introduces the color element in a renewal part. In the use of the usual color cap, all the light coming from the unit, of which the lamp is a part, does not pass through the color cap and a non-uniform color frequently results.

By means of my invention, all the useful light given off by the lighting unit is given the desired color. Moreover, the color elements are readily attached to the unit and 30 are interchangeable so that various colors may be easily and quickly secured from the unit. To permit the light to be properly directed, I have provided a holding means for the reflector which readily permits the position 35 of the reflector to be changed.

In the accompanying drawing, Fig. 1 is an elevation partially in section of a lighting unit embodying my invention; Fig. 2 is a 40 ton plan view of the color holding means; and Fig. 3 is a modification of the color element holding means.

Referring to the drawing, the lamp socket 10 is carried on the conduit 11 which is mounted on any suitable support such as a 45 wall or ceiling of a building. Attached to the lower part of the socket 10 so as to be capable of rotation about the socket is the band portion 12 of the holder. Carried by the band portion 12 are a plurality of 50 silent supporting members 13 each of which has a projection 14 near the lower end thereof which serves to engage and position the reflector 15 upon the seat formed by the out-

wardly bent portion 16 of the lower end 55 of each member 13. The parts of the supporting members are so constructed and arranged that the rotation of the holder about the socket 10, the reflector being held from rotation, produces a change in the tilt of 60 the reflector or, in other words, a change in the position or direction of the axis 17-17 of the reflector 15. This construction and arrangement, as shown, may be made by 65 making equal the lengths of two of the three supporting members 13 between the band portion 12 and the reflector engaging means while making the similarly measured length 70 of the third member 13 longer. It will be apparent that, with such a construction, as the band portion 12 is rotated and the reflector is held from rotation, the reflector will be tilted.

The reflector 15 shown in the drawing is 75 asymmetric. It has prisms 18 of the so-called stiletto type upon its outer surface and also has prisms 19 upon the screen portion 20. The bottom plane of the reflector is constructed at an oblique angle to the axis of the reflector so that the light is directed from 80 the left hand side of the reflector (Fig. 1) in the direction of the right hand side of the reflector in order to provide a greater intensity of light on the right hand side or toward the back of the show window as the unit is 85 ordinarily used. With the axis of the reflector vertical, the bottom plane of the specific reflector illustrated in Fig. 1 makes an angle of about ten degrees with the horizontal. The specific holder illustrated has 90 supporting members that hold the top plane of the reflector about five degrees from the horizontal. The rotation of the holder with respect to the reflector causes the angle of five degrees to be added to or subtracted 95 from the ten degree angle made with the horizontal by the bottom plane of the reflector when the axis 17-17 is vertical. This is illustrated in Fig. 1 in which the line a-b represents the horizontal base line and the line a-c represents the 100 bottom plane of the reflector 15 when its top plane is horizontal. When the reflector 15 is placed in the holding means so that the maximum subtraction is made from the angle b-a-c, the bottom plane is represented by the line a-d and the angle there- 105

of with the horizontal by the angle $b-a-d$ as shown in Fig. 1. When the maximum addition is made, the bottom of the reflector is represented by the line $a-e$ which makes an angle $b-a-e$ with the horizontal line.

An incandescent lamp 21 is placed in the socket 10 and a color element, consisting of an opaque or colored reflecting disc or baffle 22 surrounding the neck of the lamp and a colored light transmitting bowl or screen 23 which is placed around but preferably spaced from the lamp, is positioned to inclose substantially all of the light emitting portion of the lamp. The bowl or screen 23 has a bead 24 around the upper portion thereof which carries the disc 22 and which is engaged by the spring terminals 25 of the ends of the supporting members 13 so that the color element is supported below the reflector. The disc or baffle 22 preferably completely covers the open end of the bowl 23 so as to prevent uncolored light from passing outwardly therefrom. If preferred, the disc may be made light transmitting of the same color as the bowl. A cover cap 26 is mounted on the conduit 11 inclosing the socket 10, the upper part of the holding means and the bead 27 of the reflector 15.

The unit is assembled by attaching the band portion 12 of the holder to the socket 10, springing the supporting members 13 inwardly to pass through the aperture of the neck of the reflector 15 and releasing the members 13 so that the projections 14 engage and hold the reflector 15 which is supported on the bent portions 16. The disc or baffle 22 is then placed about the neck of the incandescent lamp 21 and the lamp inserted in the socket 10. The color bowl or screen 23 is now brought into holding engagement with the spring terminals 25 with the baffle 22 resting upon the upper edge of the bowl 23. By bringing the cover cap 26 down over the socket and upper portion of the holder, the assembly of the unit is completed. With an opaque baffle 22, the color of light emitted by the unit may be changed without disturbing the lamp 21 by detaching the color screen 23 and substituting therefor a color screen of the desired color.

It should be obvious that the color element holding means may be separate from the reflector holding means as shown in the modification of Fig. 3. In this modification, a member 28 rests on the shoulder 29 of the reflector 30 and is positioned in the aperture of the reflector by the projecting edge 31 forming part of the member 28. The resilient spring supports 32 which are attached to the member 28 engage the color screen 33 which carries the baffle 34 to carry them properly positioned within the reflector and disposed about the incandescent lamp. The reflector is supported by any

of the common supporting means such as the screws 35 which engage the groove 36 around the shoulder 29 of the reflector.

What I claim as new and desire to secure by Letters Patent of the United States is:

1. In a lighting fixture for incandescent electric lamps, a reflector, an inclosing bowl and a holder comprising means for attachment to a suitable support and rotation thereon, a plurality of supporting members having means therein for engaging said reflector, and means on each of said supporting members for engaging said inclosing bowl below said reflector, said supporting members varying in length between the attachment means and the reflector engaging means so that the rotation of the holder produces a change in the inclination of the axis of the reflector without affecting the other parts of the fixture.

2. In a lighting fixture, a light source, a reflector and means for attachment thereof to a suitable support and rotation thereon, a color element substantially enclosing the light emitting portion of the source, means for engaging said color element comprising auxiliary means for supporting said reflector, the reflector being adapted to rotate between the holder and the auxiliary engaging means to produce a change in the direction of the reflector without affecting the other parts of the fixture.

3. A lighting fixture consisting of a socket or other support and a holder comprising a metal clamping band circling the same and having depending therefrom a plurality of straps of different lengths having outwardly extending portions near their lower ends and hook shaped portions at their lower ends, a shade or reflector resting on said outwardly extending portions and a globe supported by said hook shaped portions whereby a rotation of the holder permits a change in the inclination of the axis of the reflector without affecting the other parts of the fixture.

4. A lighting fixture consisting of a support and a holder comprising a member circling the same and having depending therefrom a plurality of straps of different lengths having outwardly extending portions near their lower ends and hook shaped portions at their lower ends, a shade or reflector resting on said outwardly extending portions and a globe supported by said hook shaped portions whereby a rotation of the holder permits a change in the inclination of the axis of the reflector without affecting the other parts of the fixture.

5. In a lighting fixture, the combination with a lamp and socket or other support of a metal clamping band encircling the same and having depending therefrom a plurality of straps of different lengths hav-

ing outwardly extending portions near their lower ends and hook shaped portions at their lower ends, a shade or reflector resting on said outwardly extending portions 5 and a globe supported by said hook shaped portions whereby the lamp axis is not coincident with the axis of the globe and reflector.

6. In a lighting fixture, the combination 10 with a lamp and socket or other support of a member encircling the same and having depending therefrom a plurality of

straps of different lengths having outwardly extending portions near their lower ends and hook shaped portions at their lower 15 ends, a shade or reflector resting on said outwardly extending portions and a globe supported by said hook shaped portions whereby the lamp axis is not coincident with the axis of the globe and reflector. 20

In witness whereof, I have hereunto set my hand this 20th day of July, 1921.

LEROY C. DOANE.
